UNITED STATES PATENT OFFICE.

MARTIN HENDRICKSON, OF GLOBE, ARIZONA.

PUMP.

1,170,254.

Specification of Letters Patent.

Patented Feb. 1, 1916.

Application filed August 8, 1914. Serial No. 855,808.

To all whom it may concern:

Be it known that I, MARTIN HENDRICKSON, a citizen of the United States, residing at Globe, in the county of Gila and State of Arizona, have invented new and useful Improvements in Pumps, of which the following is a specification:

This invention is an improved pump, especially adapted for use as an irrigating pump and for operation by a windmill, steam or other engine, but also adapted for use for other purposes, the object of the invention being to provide an improved pump of this character which is cheap and simple, is very strong and durable, which may be readily installed, which may be readily disassembled to permit repairs and which requires but little power in its operation.

The invention consists in the construction, combination and arrangement of devices hereinafter described and claimed.

In the accompanying drawings: Figure 1 is a vertical central sectional view of a pump constructed in accordance with my invention. Fig. 2 is a similar view of the same on a plane at right angles to that of Fig. 1. Fig. 3 is a detail horizontal sectional view of the same on the plane indicated by the line *a—a* of Fig. 1. Fig. 4 is a detail elevation on a larger scale of one of the plungers. Fig. 5 is a vertical sectional view showing a modified form of my improved pump. Fig. 6 is a similar view on a plane at right angles to that of Fig. 5. Fig. 7 is a horizontal sectional view on a plane indicated by the line *c—c* of Fig. 5.

Referring first to the form of my invention shown in Figs. 1 to 4, inclusive, the pump casing 1 which may be made of any suitable form, is made of sections 2 which are provided at their meeting ends with outstanding flanges 3 and are detachably secured together by bolts 4 which pass through openings in said flanges, gaskets or other suitable packing devices being placed in the joints between the meeting ends of the sections. The upper section also has outturned flanges 5 at its upper end which bear on and are secured to suitable supporting timbers 6. A lower head 7 is bolted as at 8 to the lower end of the lower casing section and is provided with a pair of downwardly extending spaced cylinders 9. The pump head 10 is secured directly on the upper end of the casing and is formed with a discharge spout 11. A shaft 12 is

mounted in bearings 13 in the ends of the pump head and is provided with a pair of oppositely extending cranks 14. A pair of cylindrical plungers 15 are arranged to operate in the cylinder 9. These plungers are provided with spiders or cross pieces 16 in their upper ends. A plunger rod 18 passes through the centers of and is secured to the said spiders or cross pieces of each plunger 15 and a pair of upwardly opening valves 19 are arranged on each lower spider or cross piece 17. In the lower end of each cylinder 9 is a pair of upwardly opening valves 20. The plunger rods extend up through the casing 2 and operate in guides 21. Connecting rods 22 for their lower ends are pivotally connected to the upper ends of plunger rods as at 23 and their upper ends engaged with wrists of the cranks 14 so that when the shaft 12 is revolved by its pulley 24 the plunger rods and their plungers are caused to vertically reciprocate and to move simultaneously in reverse directions. Each plunger rod is provided with a suitable number of displacing or float members 25. Each float member comprises a pair of hollow members 26, each of which contains an air chamber 27 and these members 26 are secured on opposite sides of the plunger rods by means of bolts 28. A suitable number of these displacing or float members are employed to equal half or substantially half the cubic capacity of the casing 2. The float or displacing members on the plunger rods assist on the up strokes of the plunger rods so as to very materially reduce power required to operate the pump. Any suitable number of casing members or sections 2 will be employed, according to the depth of the well or other source of water in which the pump is arranged for operation. The casing members being detachable, and the lower head which is provided with pump cylinders being also detachable from the casing, the parts of the pump may be very readily disassembled in order to facilitate the making of repairs and hence all parts of the pump are rendered readily accessible.

In the form of my invention shown in Figs. 5 to 7 each cylinder 9 is bolted as at 29 to the lower end of a tube 30, the upper ends of said tubes being bolted as at 31 to the lower end of the casing head 32 which is provided at one side with a discharge pipe 33. The tubes 30 are provided on their opposing sides with flanged coupling mem-

bers 33, bolted together as at 34 so that the said tubes are detachably secured together. Each tube is also provided on one side with a hand hold 35 and a cover plate 36 therefor to enable access to be readily had to the plungers 37 which operate in the cylinders 9^a. The plunger rods 18^a are provided with displacement or float elements 25^a similar in construction to those hereinbefore described and which are arranged in the tubes 30. A rock shaft 38 extends transversely through the casing head 32 and is held in bearings 39 in the side walls of said casing head. One end of the rock shaft projects beyond one side of the casing head and is provided with a lever 40 to enable the pump to be operated manually if desired. A rocking yoke 41 is secured on the rock shaft and its ends are connected by means of pitmen 42 to the upper ends of the plunger rods. The pump rod 43 of a windmill may be also connected to the rocking yoke as at 44 and this pump rod extends through and is free to operate in a pipe 45 which

is connected to and leads from the top of 25 the casing head and enables the water to be lifted to the desired height.

Having thus described my invention, I claim:

The herein described pump comprising a 30 casing a pump cylinder at the lower end of the casing, a head at the upper end of the casing, a plunger arranged to operate in the cylinder; a plunger rod connected to the plunger and extending up through the 35 casing, float members arranged on two opposite sides of the plunger rod, guides in the casing for the plunger rod and engaging the latter at the sides intermediate the float members and operating means for the 40 plunger rod, arranged in the head.

In testimony whereof I affix my signature in presence of two witnesses.

MARTIN HENDRICKSON.

Witnesses:

WILLIAM G. REID,
THOS. P. VINCENT.
